BALING MACHINES

Walter Noel Powell, St. Helens, Allan Frederick Powell, Whiston, near Prescot, and Henry Anderton, Kirkby, England

Application December 10, 1957, Serial No. 701,787

6 Claims. (Cl. 100—20)

The present invention relates to pick-up or other baling machines.

Several forms of baling machines of the type referred to as pick-up balers are currently in use for baling with twine fibrous material, such as hay or straw. These machines utilize one or more knotting devices, herein-after referred to as knotters, and associated twine retaining means which operate to exert retaining forces on the twine in timed relationship with the operation of the knotters. Machines of this kind may conveniently be divided into two groups.

In one group the needle yoke is directly coupled by a connecting rod or pitman to a crank on the knotter shaft, with the consequential result that it is impossible continuously to operate the plunger or ram in compressing the fibre within the baling chamber and at the same time achieve tying of the baling twine around the compressed bales when the latter are under maximum compression, i.e. at one end of each stroke of the ram. Thus with a construction of this kind it is necessary either to stop the ram when achieving maximum compression of the material being baled and to effect tying while the ram is stopped, thereby impairing the output of the machine to the extent of one stroke of the ram each compressed bale or, as an alternative, tying must be achieved other than at maximum compression of the bale so as to return the needle to the "rest" position before the ram commences its next working stroke. Either selection, therefore, presents disadvantages and the former has an additional drawback that with automatically operated machines the first feed of each bale in the making, following a completed bale, must be twice as large as is necessary in the formation of a neat bale, thereby involving additional work or loading on the ram. Again with direct coupling of the crank on the knotter shaft with the needle yoke it is impossible for the connecting rod to retain full control of the needle to give precise needle setting throughout its entire movement and particularly when, during said movement, the elements of the direct coupling are on a straight line passing through the axis rotation of the needle yoke.

In the other group the knotter shaft has a cam the follower of which is fixed to a bell crank coupled to the needle yoke by a connecting rod. In constructions of this kind the profile of the cam is of necessity severe with the result that a heavy strain is imparted to the mating components and assemblies causing play or worn joints after a relatively short working life to the detriment of precision in needle adjustment.

The primary object of the present invention is to retain the benefits of the known constructions without their respective disadvantages, and in particular firstly to insert the baling twine into its retainer or clamp for the tying operation at the instant when the fibre in the baling chamber is under maximum compression from the reciprocating ram or plunger, and return the needle to its inoperative or rest position before the ram commences

2

its working stroke, secondly to retain maximum control of the needle throughout its entire cycle of operations and particularly when the ram is at the end of its compression stroke, and thirdly to facilitate precise adjustment of the needle relatively to the knotter.

According to the present invention a roller or pin revolving with, and about the axis of, the knotter shaft engages with a curved track or slide of a sprocket or the like rotary member which in turn is coupled, by an endless chain or the like flexible driving means, to the shaft about which the needle yoke is angularly displaced, the curvature or profile of the track or slide being such that reciprocatory motion is imparted to both rotary members associated with the flexible drive on unidirectional rotation of the knotter shaft.

In this way reciprocatory arcuate displacement of each needle about the axis of the shaft on which its yoke is mounted may be initiated at any desired position of rotation of the knotter shaft, and as the latter is displaceable in unison with the ram or plunger it follows that each needle may commence its operative movement at any position of the ram determined by the curvature or profile of the roller track or slide.

The invention is more particularly described with reference to the accompanying drawings which illustrate one form of construction by way of example and in which:

Figures 1-6 illustrate diagrammatically successive stages in the longitudinal displacement of the ram or plunger during its final compression stroke and the relative positions of angular displacement of the knotter shaft about its own axis together with the relative positions of the needle at each of said successive stages.

Figure 7 is a perspective from the view showing the relationship between the knotter shaft and one of the rotary members of the flexible drive at one stage of angular displacement of said shaft.

Figure 8 is a perspective view taken from another position of the same elements and at the same stage of angular displacement of the knotter shaft, this perspective view showing a knotter and a twine retaining member carried by a body on, and rotating with, said shaft.

Figure 9 is a side view of the mechanism shown in Figures 7 and 8 in a position consistent with the first stage of the operative association of the various parts as diagrammatically represented in Figure 1.

In the drawings the knotter shaft is shown at 10 and has mounted on it a body 11 carrying the knotter (not shown) and a twine retainer which comprises a stationary base 12 and a hook member 13 angularly displaceable about an axis 14 with respect to said base (Figure 8) when it is desired to operate the knotter, the said hook member 13 being normally maintained under pressure against the base 12 by means of a spring 15 until it is desired to reduce said pressure during the required period of the knotting and twine severing operation when the spring 15 is automatically displaced. A knotter assembly of this kind has already been proposed and forms no part of the present invention.

The shaft 10 has rotating with it a crank 16 carrying a pin or roller 17 which engages within a curved roller track or slide constituted by a slotted arm projecting radially at its inner end 18 from a driving sprocket 19, or from a plate rigidly connected to or integral with said sprocket, the

remaining part 20 of said arm being curved to extend about an arc subtending an angle of approximately 90° about the axis of the knotter shaft 10 and in a direction opposite to the direction of rotation of said shaft as indicated by the arrow 21.

The sprocket 19 is connected by an endless chain 22, the tension of which is varied in any desired manner such as for example by the means shown in Figure 7, with a

smaller sprocket 23, the shaft 24 of which carries an arm 25 at the outer end of which is mounted a needle yoke 26. It will be seen that on angular displacement of the sprocket 19 in a clockwise direction about its axis the needle yoke is angularly displaced about the shaft 24 in a clockwise direction but to a greater extent dependent upon the ratio of the effective diameters which has been predetermined for the sprockets 19, 23. Thus with one complete rotation of the sprocket shaft 10 about its axis the pin or roller 17 revolves once around said axis and in so doing it imparts to the curved track or slide 18, 20 a to and fro arcuate movement about the axis of the sprocket 19 and with a dwell at the end of the return movement, thereby causing the needle yoke 26 to be given a reciprocating displacement over a greater arc or throw than that of the track or slide, dependent on the predetermined selection of the relative sprocket sizes, and with a similar dwell at the end of the return displacement of the needle yoke to its inoperative position.

In the example illustrated in the drawings the roller track 18, 20 and its sprocket 19 are angularly displaced to and fro about the axis of the latter through an arc of approximately 85° during three-quarters of a complete rotation of the knotter shaft 10 while the pin or roller 17 engages with the inner end 18 of the track and remains stationary during the remainder of said rotation, i.e. while the pin 17 engages with the curved part 20 of the track. Further in the particular construction illustrated, the relative sizes of the sprockets 19, 23 are such that the needle yoke is rotated through an arc of 118° simultaneously with the reciprocating arcuate movement of the track or slide through a stroke of 85°. An arcuate displacement of this extent is sufficient to displace each needle 26 wholly into and out of the region of the twine retainer or clamp.

The baling chamber is diagrammatically indicated at 27 and the ram for compressing the bales within the chamber is shown at 28. The ram is slotted longitudinally to permit the needle to pass through it from one side to the other when the ram lies in the arcuate path of travel of the needle 26 and the twine 31 carried thereby about the axis of the shaft 24. It is driven through connecting rods 29, 30 from a power source (not shown) which may be the power take-off from a tractor adapted to haul the machine or may be on the machine itself. This power source is also adapted to drive the knotter shaft 10 through a trip device (not shown) which energizes the shaft 10 solely after a predetermined number of strokes of the ram have been completed for partially compressing the bale built up within the chamber 27 and the ram is about to commence its final stroke of compression on said bale. At such time the trip device is operated whereby the shaft 10 is caused to make a complete rotation about its axis before becoming de-energised.

The actual sequence of operations in succession is represented by Figures 1-6. Thus in Figure 1 the ram 28 has started on its final compression stroke to compress a bale within the chamber 27 and during this portion of the stroke of the ram the knotter shaft 10 rotates in an anti-clockwise direction with the pin or roller 17 located within the arcuate portion 20 of the track carried by the sprocket 19. As a result the latter remains stationary. The sprocket 19 commences to rotate in a clockwise direction about its own shaft when the pin or roller 17 enters the straight or radial inner end 18 of the track as shown in Figure 2 and in this position the ram has travelled beyond the mid point of its compression stroke and into the path of the rotatable needle 26. Further anticlockwise rotation of the shaft 10 and displacement of the ram 28 bring the elements into the positions shown at Figures 3 and 4, and in the latter figure the ram is shown in its extreme forward position consistent with maximum compression of a bale within the chamber 27. It is in this position that the acts of tying the bale by means of the twine 31 fed to the knotter 12, 13, and severing of the twine, are about to be accomplished.

In completing a single rotation in an anti-clockwise direction through 360° the shaft 10 through the pin or roller 17 causes the track 18 and sprocket 19 to rotate about the axis of the latter, but in an anti-clockwise direction, i.e. opposed to their earlier movement and in the result the needle 26 is brought back to its inoperative position of rest through the positions illustrated successively in Figures 5 and 6. During this period the ram 28 is retracted as shown.

It will be appreciated that variations or modifications of the construction described and illustrated in the drawings may be adopted without departing from the scope and spirit of the invention. The specification and drawings accordingly should be regarded in an illustrative rather than a restrictive sense.

We claim:

1. In a baling machine having a repeatedly reciprocated ram for compressing a bale to be tied, a knotter shaft intermittently rotated through a single revolution in one direction and a needle yoke mounted for swinging movement about a related shaft; the combination of a rotary member, a curved track defining member fixed to said rotary member for movement with the latter, a drive member slidably engaging in said curved track and being fixed to the knotter shaft at a location spaced radially from the axis of the latter to turn with the knotter shaft and thereby effect oscillation of said rotary member in response to rotation of the knotter shaft in said one direction, and flexible transmission means between said rotary member and the needle yoke so that the latter is oscillated upon oscillation of said rotary member.

2. In a baling machine, the combination as in claim 1; wherein said flexible transmission means includes a drive chain engaging said rotary member and driven by the latter, and a sprocket fixed relative to the shaft of the needle yoke and turnable about the axis thereof, said sprocket being engaged by said drive chain.

3. In a baling machine, the combination as in claim 2; wherein said rotary member has a generally circular periphery engaged by said drive chain, and said rotary member further includes means adjustable tangentially relative to said periphery of the rotary member and securing the opposite ends of the drive chain to the rotary member, thereby to provide for adjustment of the tension in said drive chain.

4. In a baling machine, the combination as in claim 1; wherein said track includes a relatively straight portion extending radially with respect to the axis of said rotary member and a curved end portion having a radius of curvature approximately equal to the radial distance of said drive member from said axis of the knotter shaft so that said rotary member is oscillated, during movement of said drive member along said relatively straight portion of the track, and remains stationary during movement of the drive member along said curved end portion of the track.

5. In a baling machine, the combination as in claim 4; wherein said curved end portion of the track has an angular extent of approximately 90 degrees.

6. In a baling machine, the combination as in claim 4; wherein said axis of the rotary member is parallel to, and spaced from the axis of the knotter shaft by a distance greater than said radial distance from the drive member to the axis of the knotter shaft so that said rotary member has a single to and fro oscillation imparted thereto during a single revolution of the knotter shaft in said one direction.
